ABSTRACT

A target senses whether and where it has been struck by a laser light. The target includes a screen for allowing laser light to pass through, a plurality of light sensors behind the screen, and an optical display associated with one or more of the light sensors. When the target is struck by a laser light, a sensor records the strike, and the target may be struck with laser light multiple times, whereby different sensors may record the different strikes. To determine whether and where the target has been struck, the user activates a display mode that causes the optical displays in the target to illuminate. The user can then reset the target so the user can begin again.

LASER TRAINER TARGET

CROSS REFERENCE TO RELATED APPLICATIONS

This application is a continuation of U.S. application Ser. No. 13/353,241, entitled LASER TRAINER TARGET, filed on Jan. 18, 2012 and claims priority to and incorporates by reference the disclosure of U.S. Provisional Patent Application No. 61/433,902 entitled LASER TRAINER CARTRIDGE AND LASER TRAINER TARGET, filed on Jan. 18, 2011. The disclosure of co-pending U.S. application Ser. No. 13/353,165 entitled "Laser Trainer Cartridge" to Larry E. Moore, filed on Jan. 18, 2012 is incorporated herein by reference.

FIELD OF THE INVENTION

The present invention relates to firearm training systems that do not require live ammunition.

SUMMARY OF THE INVENTION

Conventional firearms training can be dangerous, expensive (considering the prices for ammunition and replacement targets) and can only be performed in certain areas, such as shooting ranges. The present invention allows firearm training to be performed safely, inexpensively, and almost anywhere without the use of live ammunition.

A laser trainer target according to aspects of the invention records where a laser light (such as the laser emitted from a laser trainer cartridge) hits the target. Among other things, the laser trainer target (or "target") can help save time, money and ammunition (which is itself expensive), and can help users learn or teach shooting skills, preferably including unsighted fire, accuracy, grouping and trigger control. The laser trainer target helps users to practice shooting skills in a wide range of locations.

The laser trainer target displays hits from laser light when the target is activated to be in the display mode. In one embodiment, a user "shoots" laser light at the target and, to display the hits to the target, shoots and strikes a "display" area on the face of the laser trainer target with laser light. When the user is finished training, he/she simply strikes a "reset" area of the target with laser light, which resets the target so it no longer registers laser light strikes that occurred before the target was reset.

The laser trainer target provides a convenient, easy-to use, and inexpensive firearms training option, and operates without the need for an external computer, television or projector. In alternate embodiments, however, a target of the present invention may be configured to interface with any desired device, such as a computer system, printer, and/or display. In this way, users can, among other things, compare their scores against one another and print out paper hard-copies of their targets (showing, for example, simulated bullet holes) just as they would have at an actual shooting range.

BRIEF DESCRIPTION OF THE DRAWINGS

FIGS. 1 and 2 are perspective and frontal views of a laser trainer target according to aspects of the present invention.

FIG. 3 illustrates various aspects of the target in FIGS. 1 and 2, including how the back of the target can be removed

to insert or replace batteries, how the target is used, how impacts of laser light on the target are displayed, and how the target is reset.

FIGS. 4A-AJ schematically illustrate components in an exemplary laser training target according to various aspects of the invention.

FIG. 5 is a close-up view of section "A" in FIG. 4H, showing the circuit diagrams for a portion of the sensors used in the laser training target.

FIGS. 6-8 are close-up views of section "B"- "D", respectively, in FIGS. 4I, 4F, and 4C, each showing a microcontroller used by the laser training target.

FIG. 9 is a close-up view of section "E" in FIG. 4B, showing the circuit diagrams for the "Display" and "Reset" portions of the laser training target.

FIG. 10 is a close-up view of section "F" in FIG. 4D.

FIG. 11 is a close-up view of section "G" in FIG. 4J, showing the circuit diagrams for a portion of the light-emitting diodes used in the laser training target.

DETAILED DESCRIPTION OF THE INVENTION

Turning now to the figures, where the purpose is to describe a preferred embodiment of the invention and not to limit same, FIGS. 1 and 2 are perspective and frontal views, respectively, of an exemplary embodiment of a laser trainer target 10 according to various aspects of the invention. The target 10 includes a screen 12 (circular with a bullseye pattern in this embodiment) that allows laser light to pass through it. Behind the screen are a plurality of sensors (e.g., phototransistors) configured to detect when it has been exposed to laser light, and an optical display (e.g., a light-emitting diode) associated with each of the sensors capable of showing where the laser light struck the target when activated.

The operation of the target of FIGS. 1 and 2 is further shown in FIG. 3. As shown in FIG. 3, the target is battery-powered (using three "AA" batteries) 11, although any suitable power source may be utilized, such as electricity from an outlet in a home, and includes a manual on-off switch 14. This exemplary target 10 also includes a display area 18 and a reset area 20. When the display area 18 is illuminated (or "struck") by a laser light, it activates the display mode, which illuminates the optical display(s) D to indicate where the target 10 was previously struck by laser light. When the reset area 20 is illuminated by laser light, each sensor S that was struck by laser light is reset and each optical display D is turned off. The sensors S are not activated again until struck again by laser light. In this manner, the target 10 can be used and reset over and over.

In this embodiment, the laser trainer target 10 gives the user delayed shooting feedback, so the shooter can concentrate on the next shot instead of visually seeing where the last shot struck. In this embodiment, the three AA batteries 11 can sense and register about 6,000 hits (or "strikes"), and target 10 can sense and register hits by a laser of up to 50 yards away. In alternate embodiments, hits may be displayed as soon as they are registered, and/or the "display," "reset," and "on/off" functions of the target 10 may be controlled via a remote control in communication with the target through a wired or wireless interface.

FIGS. 4A-AJ depict an exemplary circuit diagram of the laser trainer target shown in FIGS. 1-2. In this embodiment, the laser trainer target 10 includes 62 sensors S (the phototransistors shown in Section "A" of FIG. 5) and 62 optical displays D, which are preferably laser-activated LED lights

(shown in Section “G” of FIG. 11). Detection of laser strikes and illumination of the optical displays D is controlled by three microcontrollers M (Sections “B,” “C,” and “D” in FIGS. 6-8, respectively). Section “E” of FIG. 9 illustrates the phototransistor sensors and switching used in the display and reset areas of the target 10.

Preferably, each sensor S and its corresponding optical display D are located in the same position (or very near to each other) behind the target screen 12 to show a laser hit as accurately as possible when the target 10 is in the display mode. A target of the present invention may be of any suitable size, shape and color. In the exemplary embodiment depicted in FIGS. 1 and 2, the screen 12 of the target 10, as well as the reset and display areas 18 and 20, are red in order to operate optimally with red laser light. A target of the present invention may include any desired number of sensor/optical display pairs, which may have any desired spacing. In the embodiment depicted here, there are 62 sensor/display combinations spaced about 1/2" apart. The target may also, for example, have sensor/display pairs spaced in a circular pattern spaced 1" apart expanding from the center of the target.

Preferably, only a single sensor/display pair is activated for each laser strike. In one embodiment, this can be accomplished by, for example: (a) only activating the display D corresponding to the sensor S that received the highest intensity laser light strike, and (b) delaying the activation of any other sensor/display pairs (which could be done by delaying the activation of one or more of the sensors and displays), by a predetermined amount of time, to avoid the target registering a single laser strike more than once. The predetermined delay is preferably long enough to not register a laser “dragged” across the target, but short enough to register hits from a person rapidly pulling the trigger on a firearm equipped with a laser-emitting device (such as a laser trainer cartridge). In one embodiment, there is a 25 ms delay between the permissible registration of laser strikes. During the delay the sensors S are deactivated from recording additional strikes.

In one embodiment, when a sensor S detects a laser strike, the strike is registered (either by the sensor or a microcontroller in communication with the sensor) until the reset function is activated. In some embodiments, multiple laser strikes upon the same sensor may be indicated by increasing the intensity of the light emitted from the optical display when the target 10 is in the display mode.

In one embodiment, the target may produce a sound (e.g., through a speaker) to indicate the target has been hit, as well as to indicate where on the target 10 the laser strike was registered. For example, one type of sound may be produced to indicate a “bulls-eye” while other sounds may be produced to indicate, respectively, a hit within each of the rings of the target.

The functionality of the laser training target 10 may be implemented using hardware, software, or combination of the two. In the exemplary target of FIG. 1, the microcontrollers M (FIGS. 6-8) execute instructions stored in a memory (either internal to the microcontroller M or external to the microcontroller M) to cause the processors to register laser strikes from the sensors S and illuminate the optical displays when the target 10 is in the display mode. As an alternative to the manual on/off switch 14 and display or reset areas 18 and 20 of the target 10, alternate embodiments of the target may be configured to interface to a remote control (e.g., a dedicated remote or application running on a device, such as a computer, in communication with the target) to perform various functions, including resetting the

target, activating the display function of the target, turning the target on and off, adjusting an intensity level of one or more of the optical displays, and adjusting a volume level of one or more sounds produced by the target.

Having thus described some embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

15 What is claimed is:

1. A target for sensing a laser light striking the target, the target comprising (a) a screen for allowing laser light to pass through it; (b) a plurality of sensors, each of the sensors for 20 sensing when it has been exposed to laser light; and (c) a plurality of optical displays, at least one of the plurality of optical displays being associated with each of the sensors, each optical display capable of being activated to display on the target where the laser light struck the target.

2. The target of claim 1 that is battery powered.
3. The target of claim 1 that has a manual off-on switch.
4. The target of claim 1 wherein the target area that is circular in shape.

5. The target of claim 1 wherein each of the optical 30 displays is a light emitting diode.

6. The target of claim 1 that has a display mode wherein each of the optical displays that is associated with a sensor that has been exposed to laser light illuminates when the display mode is activated.

7. The target of claim 6 wherein the display mode is activated by illuminating a display area on the target by a laser light.

8. The target of claim 1 wherein each sensor that is struck by laser light records the strike of laser light until the target is reset.

9. The target of claim 1 wherein each sensor is in electrical communication with an optical display located at the same relative position on the target as the sensor.

10. The target of claim 1 wherein the sensors are positioned 1/2" apart.

11. The target of claim 1 wherein the sensors are positioned in a circular pattern on circles spaced 1" apart expanding from the center of the target.

12. The target of claim 1 wherein only one sensor is activated for each laser light strike.

13. The target of claim 1 wherein a laser light strike on the target activates the sensor that senses the highest light intensity from the strike and the other sensors are deactivated with respect to that laser light strike.

14. The target of claim 1 wherein the target is configured to emit a sound when a laser strike is detected.

15. The target of claim 1 wherein a laser light strike on the target activates the sensor that senses the highest light intensity from the strike and the other sensors are deactivated with respect to that laser light strike.

16. The target of claim 1 wherein the sensors are deactivated for 25 milliseconds or more before reactivating.

17. The target of claim 1 wherein the target is configured to emit a sound when a laser strike is detected.

18. The target of claim 1 further comprising a remote control configured to control the target, wherein controlling the target includes one or more of:

resetting the target;
 activating the display function of the target;
 turning the target on;
 turning the target off;
 adjusting an intensity level of one or more of the optical displays; and
 adjusting a volume level of one or more sounds produced by the target.

19. A target for sensing a laser light striking the target, the target comprising (a) a screen for allowing laser light to pass through it; (b) a plurality of sensors, each of the sensors for sensing when it has been exposed to laser light; (c) a plurality of optical displays, at least one of the plurality of optical displays being associated with each of the sensors, each optical display capable of being activated to display on the target where the laser light struck the target; and (d) wherein the sensors are activated for 25 milliseconds or more before being reactivated.

20. The target of claim 19 that is battery powered.

21. The target of claim 19 that has a manual off-on switch.

22. The target of claim 19 wherein each of the optical displays is a light emitting diode.

23. The target of claim 19 that has a display mode wherein each of the optical displays that is associated with a sensor that has been exposed to laser light illuminates when the display mode is activated.

24. The target of claim 19 wherein the display mode is activated by illuminating a display area on the target by a laser light.

25. The target of claim 19 wherein each sensor that is struck by laser light records the strike of laser light until the target is reset.

26. The target of claim 19 wherein each sensor is in electrical communication with an optical display located at the same relative position on the target as the sensor.

27. The target of claim 19 wherein the sensors are positioned 1/2" apart.

28. The target of claim 19 wherein the sensors are positioned in a circular pattern on circles spaced 1" apart expanding from the center of the target.

29. The target of claim 19 wherein only one sensor is activated for each laser light strike.

30. The target of claim 19 wherein a laser light strike on the target activates the sensor that senses the highest light intensity from the strike and the other sensors are deactivated with respect to that laser light strike.

31. The target of claim 19 wherein the target is configured to emit a sound when a laser strike is detected.

32. The target of claim 19 further comprising a remote control configured to control the target, wherein controlling the target includes one or more of:

resetting the target;
 activating the display function of the target;

turning the target on;
 turning the target off;
 adjusting an intensity level of one or more of the optical displays; and
 adjusting a volume level of one or more sounds produced by the target.

33. A target for sensing a laser light striking the target, the target comprising (a) a screen for allowing laser light to pass through it; (b) a plurality of sensors, each of the sensors for sensing when it has been exposed to laser light; and (c) a plurality of optical displays, at least one of the plurality of optical displays being associated with each of the sensors, each optical display capable of being activated to display on the target where the laser light struck the target; and (d) a remote control configured to control the target, wherein controlling the target includes one or more of:

resetting the target;
 activating the display function of the target;
 turning the target on;
 turning the target off;
 adjusting an intensity level of one or more of the optical displays; and
 adjusting a volume level of one or more sounds produced by the target.

34. The target of claim 33 that is battery powered.

35. The target of claim 33 that has a manual off-on switch.

36. The target of claim 33 wherein each of the optical displays is a light emitting diode.

37. The target of claim 33 that has a display mode wherein each of the optical displays that is associated with a sensor that has been exposed to laser light illuminates when the display mode is activated.

38. The target of claim 33 wherein the display mode is activated by illuminating a display area on the target by a laser light.

39. The target of claim 33 wherein each sensor is in electrical communication with an optical display located at the same relative position on the target as the sensor.

40. The target of claim 33 wherein the sensors are positioned 1/2" apart.

41. The target of claim 33 wherein the sensors are positioned in a circular pattern on circles spaced 1" apart expanding from the center of the target.

42. The target of claim 33 wherein only one sensor is activated for each laser light strike.

43. The target of claim 33 wherein a laser light strike on the target activates the sensor that senses the highest light intensity from the strike and the other sensors are deactivated with respect to that laser light strike.

44. The target of claim 33 wherein the target is configured to emit a sound when a laser strike is detected.
